UNITED STATES PATENT OFFICE.

REINHOLD H. WAPPLER, OF NEW YORK, N. Y., ASSIGNOR TO DANIEL T. GARRIE, OF NEW YORK, N. Y.

THERAPEUTIC ELECTRIC APPARATUS.

1,092,878.

Specification of Letters Patent. Patented Apr. 14, 1914.

Application filed August 12, 1913. Serial No. 784,335.

To all whom it may concern:

Be it known that I, REINHOLD H. WAPPLER, a citizen of the United States, residing at New York city, county and State of New York, have invented a new and Improved Therapeutic Electric Apparatus, of which the following is a specification.

This invention relates to a novel therapeutic apparatus for generating an electric current adapted to be applied to a patient's body, and more particularly to novel means for automatically effecting a rhythmic swelling of said current whereby the therapeutic effect thereof is considerably augmented.

The invention also comprises novel means for regulating the strength of the current to be applied and other novel features more fully brought out in the specification and appended claims.

In the accompanying drawing: Figure 1 is a plan of an apparatus embodying my invention; Fig. 2, a front elevation thereof; Fig. 3, a longitudinal section through the induction coil and connected parts; Fig. 4, an end view of the interrupter; and Fig. 5, a wiring diagram.

My improved therapeutic apparatus comprises essentially an induction coil A, within a central axial bore of which is accommodated a core B that receives reciprocating movement from a suitable source of energy, such as an electromotor C. Induction coil A is shown to consist of an inner tube 10 and a concentric outer shell 11 which is spaced therefrom for the accommodation of a primary coil 12, the length of said coil being considerably less than that of tube 10 and shell 11, as clearly illustrated in Fig. 3. At one end, tube 10 is fitted into the corresponding bore of an upright 13 carried by base plate 14, while at the other end, a ring 15 is interposed between said tube and shell 11, which ring is by screw 16 secured to a post 17 of base plate 14. Within tube 10 is slidably accommodated the core B that consists of a cylinder 18 and an inclosed bundle of soft iron wires 19. Cylinder 18 is, by link 20 and screw 21, connected to a worm disk 22 which engages the worm 23 carried by the shaft 24 of electromotor C. Coil 12 is, by wire 25, connected to the primary coil 26 of an interrupter D, said coil being in turn conductively connected by wire 25^a to the vibratory armature 27 that is adapted to in-

termittently engage a contact screw 28. The latter is, by wire 29 connected to a condenser E which is in turn by wire 30 connected to armature 27. One pole of a battery F is by wire 31, switch G, and wire 32, adapted to be connected to wire 29, while the other pole of the battery is by wire 33 connected to primary coil 12, said wire being also connected by wire 34 to a binding post I. A binding post II is by wire 35 connected to an intermediary section of coil 12, while binding posts III and IV are respectively connected by wires 36, 37 to wire 30, 29. Electromotor C receives its current from a suitable source of electricity (not shown) which is so connected to the motor that by correspondingly operating a switch H, the number of revolutions of said motor may be altered at will. Binding posts I, II, III, IV are adapted to be coupled to the electrodes (not shown) that are brought into contact with the patient to be treated, the selection of the proper post-pairs depending upon the strength, etc., desired of the current to be applied.

As thus far described, it will be seen that by closing switch G, an induction current will be produced, that flows from battery F through the parts 33, 12, 25, 26, 25^a, 27, 28, 29, 32, G, 31 back to battery F. This current may be applied to the patient in the desired strength by properly selecting the binding posts I to IV to which the electrodes are to be connected. Thus by connecting the electrodes to posts IV and III a current of maximum strength may be obtained, while by using binding post III, II or I, currents of respectively medium or low strength may be produced. By closing switch H, the rod B is automatically oscillated within induction coil A so that the current applied to the patient is alternately increased and decreased so as to produce a periodical contracting and releasing effect upon the muscles, nerves, etc., to be treated whereby superior therapeutic results are obtained.

In order to regulate the strength of the maximal current applied, during the operation of the apparatus, a short-circuited secondary coil 38 is slidably mounted on tube 11, said coil being shown in Figs. 1 to 3, to consist of a single winding which is made in the form of a tubular metallic slide 38^a.

This slide is preferably graduated as at 39, which graduations coöperate with a stationary index 40 secured by screw 16 to post 17. By moving slide 38^a from the left toward the right (Figs. 1 to 3) the strength of the current is gradually increased.

In order to reduce the undesirable inductive effect of the sparks formed on breaking contact between the parts 27, 28, winding 26 is preferably surrounded by a short-circuited secondary winding 41. In this way, the operative current applied to the patient may be reduced to a minimum if so desired.

15 I claim:

1. A therapeutic apparatus, comprising an induction coil, an interrupter in circuit therewith, and automatic means for gradually increasing and decreasing rhythmically 20 the strength of the current passing through said induction coil.

2. A therapeutic apparatus comprising an induction coil, a core slidably mounted therein, and automatic means for reciprocating 25 said core.

3. A therapeutic apparatus comprising an induction coil, a core slidably mounted therein, an electromotor, and means actuated by said electromotor for reciprocating 30 the core.

4. A therapeutic apparatus comprising an induction coil, a core slidably mounted therein, an electromotor, a worm secured to the electromotor-shaft, a worm disk engaged by said worm, and a link for operatively connecting said disk to the core.

5. A therapeutic apparatus comprising an induction coil having a primary winding and a short-circuited secondary winding adjustable along said primary winding, an 40 interrupter in circuit with the primary winding, and automatic means for periodi-

cally varying the strength of the current passing through said primary winding.

6. A therapeutic apparatus comprising an 45 induction coil having a primary winding and a short-circuited secondary winding adjustable along said primary winding, an interrupter-coil in circuit with said primary winding, an interrupter-armature conductively connected to the interrupter-coil, a contact adapted to be intermittently engaged by said armature, a condenser in circuit with said armature and contact, a core 50 slidably mounted within the induction coil, and a motor for reciprocating said core.

7. A therapeutic apparatus comprising an induction coil having a primary winding and a short-circuited secondary winding adjustable along said primary winding, an interrupter-coil having a primary winding in circuit with the primary winding of the induction coil and a short-circuited secondary winding, an interrupter-armature conductively connected to the interrupter-coil, a 55 contact adapted to be intermittently engaged by said armature, a condenser in circuit with said armature and contact, a core slidably mounted within the induction coil, and a motor for reciprocating said core.

8. A therapeutic apparatus comprising an induction coil, a member movable in a direction parallel to the axis of said coil and adapted to control the strength of the current passing through said coil, and automatic means for reciprocating said member whereby the strength of the current is gradually increased and decreased in rhythmical manner.

REINHOLD H. WAPPLER.
